(57) **CLAIM**

(**) Term: **14 Years**

What is claimed is the ornamental design for a housing for a mobile computing device, as shown and described.

(21) Appl. No.: **29/317,772**

(22) Filed: **May 6, 2008**

DESCRIPTION

(51) **LOC (9) Cl.** **14-02**

FIG. 1 is a leftward front isometric view of a housing for a mobile computing device;

(52) **U.S. Cl.** **D14/341**

FIG. 2 is a rightward front isometric view thereof;

(58) **Field of Classification Search** D14/341–346;

FIG. 3 is a front view thereof;

D18/1, 2, 7, 11; 235/145 A, 145 R; 341/22,

341/23, 156, 168, 169, 172, 173; 349/12;

361/680–686, 690–696

See application file for complete search history.

FIG. 4 is a leftward side view thereof;

(56) **References Cited**

FIG. 5 is a rightward side view thereof;

U.S. PATENT DOCUMENTS

FIG. 6 is a bottom end view thereof;

D494,166 S * 8/2004 Kumagai et al. D14/345

FIG. 7 is a top end view thereof; and,

D558,757 S * 1/2008 Andre et al. D14/341

FIG. 8 is a back view thereof.

D561,159 S * 2/2008 Heng et al. D14/138

The broken lines shown in the drawings are for the purpose of

503 illustrating portions of the housing for a mobile computing

device and form no part of the claimed design.
